DRAPERY SUPPORTING DEVICE

Application filed October 26, 1929. Serial No. 402,573.

The invention relates generally to drapery supporting devices; and more especially to so-called "French heading hooks," as well as the ordinary drapery hook, suitable for use in hanging traversing curtains, portières, draperies, etc., as on a pole or rod along which they may be drawn by suitable traverse cords or the like. Heretofore, various expedients have been resorted to for keeping such hooks from shifting with reference to a curtain, as through slipping or sliding thereon of the thread by which they are attached to said curtain.

It is the object of the present invention to construct of wire a hook of this character in such a manner that the same may be so sewed to the curtain as to prevent shifting of the hook relatively thereto, more especially obviating a longitudinal displacement of said hook.

A further object of the invention resides in a construction of heading or drapery hook which, when in place, can not become entangled with the traverse cord, nor dislodged from its attached ring.

To this end, the invention comprises a one-piece hook constructed of a suitable length of wire and formed with an eye portion terminating in a short laterally projecting prong or out-turned end which affords with an adjacent shank portion of the hook a neck member about which thread is to be sewed in attaching the hook to the fabric. The said hook may, furthermore, be provided with an elongated prong for fitting through an eye of a curtain ring as used in mounting the curtain or drapery by means of said hooks upon a pole or rod. The free end of the said prong, moreover, may then be located in juxtaposition to the eye portion of the hook, being adapted to fit within and to be held by said eye or by a further eye provided thereon.

As a result of this arrangement, not only is the novel supporting device provided with means to insure against shifting relatively to its attached fabric and adapted for being securely retained thereto, but the usual prong associated therewith for carrying the supporting curtain rings may be disposed, after

attachment of the device, in such a manner that the traverse cord is prevented from getting beneath the said prong to interfere with free action while traversing the curtain. Furthermore, the hook is thereby also secured against dislodgement from its ring. 53

The nature of the invention, however, will best be understood when described in connection with the accompanying drawings, in which:

Fig. 1 is a front view of the novel supporting device as embodied in a heading hook which is shown attached to a curtain.

Fig. 2 is a side elevation of the hook.

Fig. 3 is a side elevation and part section showing the hook attached to a curtain ring.

Fig. 4 is a front elevation, and Fig. 5 a side elevation illustrating a simplified form of the hook, as of the ordinary drapery type.

Referring to the drawings, more particularly Figs. 1 to 3 thereof which set forth the heading type, the hook is illustrated as constructed of a single piece of wire looped at its opposite ends to provide the upper and lower eyes 10 and 11, respectively. The free end of the wire at the upper eye 10, moreover, is shown bent laterally outwardly as a prong or out-turned end 12 which forms with a portion 13 of the intermediate shank 14 a neck thereat about which thread 15 is to be sewed in attaching the hook to fabric as the curtain 16. Of course, further sewings 17 and 18 are had at different portions of the respective eyes 10 and 11; but particularly due to the threads 15 will the hook be secured against displacement longitudinally of the curtain because of the contracted neck portion. 70 76 80

At the other eye 11 the wire is continued upwardly along the shank a short distance, affording a further neck for a sewing 19 and is bowed backwardly beyond same as at 20 to accommodate a ring, as hereinafter set forth. The wire is then continued upwardly and bent forwardly and downwardly forming at its uppermost portion the eye 21 and at its extremity the prong 22. 85 90

By means of this prong the hook may be attached to the ring 23, Fig. 3, in the usual manner, the eye 24 thereof being held in the eye 21 of the prong member. Furthermore, 100

the end of prong 22 is preferably located in juxtaposition to the eye 11 and is of such a length that, after the ring has been inserted, it may be sprung into said eye 11 to keep its free end from interfering with the traversing cord 25 as the same cannot then get behind said prong. This securing of the prong end will also serve to close the eye 21 to prevent the hook from becoming dislodged from its 10 ring.

In Figs. 4 and 5, a simplified form of hook is shown, being of the ordinary drapery hanging type not intended for heading purposes. In this embodiment, but a single eye 26 is provided and at the lowermost portion of the hook, the free end of the wire at this point being bent laterally outwardly as at 27 to afford with the shank portion of the hook a contracted neck portion 28 about which the 20 thread may be sewed, as in the previously described embodiment. A prong 29 is then provided by bending over the wire in the plane of its shank, said prong having at its upper portion the eye 30, while its lower free 25 end is preferably located in juxtaposition to the eye 26 and adapted for locking therein when a ring (not shown) has been attached to said hook, as in the previously described embodiment.

30 By the foregoing expedients, a hook may be readily secured against displacement on a curtain, drapery or like fabric to which it is attached; and, moreover, its ring-attaching prong will not interfere with the curtain or 35 with the traversing cord thereof after the rings have been inserted for suspending the curtain.

I claim:

- 40 1. A one-piece hook for suspending fabrics, comprising a wire with shank portion and formed at one end with an eye and the wire terminating thereat in a lateral projection adjacent a portion of the shank to afford a neck therewith about which the hook may be sewed to the fabric.
- 45 2. A one-piece hook for suspending fabrics, comprising a wire with shank portion and formed at one end with an eye and the wire terminating thereat in a lateral projection adjacent a portion of the shank to afford a neck therewith about which the hook may be sewed to the fabric, and the wire being bent also into an outwardly extending ring prong.
- 50 3. A one-piece hook for suspending fabrics, comprising a wire with shank portion and formed at one end with an eye and the wire terminating thereat in a lateral projection adjacent a portion of the shank to afford a neck therewith about which the hook may be sewed to the fabric, and the wire being bent at the opposite end also into an outwardly extending ring prong whose free end is located in juxtaposition to said eye for engagement 55 therewith.

4. A one-piece heading hook for suspending fabrics, comprising a wire formed with a pair of oppositely disposed eyes and with intermediate shank portion, the wire terminating at one of said eyes in a lateral projection adjacent the shank portion to afford a neck therewith about which the hook may be sewed to the fabric, and the wire being also bent into an outwardly extending ring prong. 70

5. A one-piece heading hook for suspending fabrics, comprising a wire formed at its opposite ends with eyes and with intermediate shank portion, the wire terminating at one of said eyes in a lateral projection adjacent the shank portion to afford a neck therewith about which the hook may be sewed to the fabric, and the wire being also bent into an outwardly extending ring prong whose free end is located in juxtaposition to the other eye for engagement therewith. 75

6. A one-piece heading hook for suspending fabrics, comprising a wire formed with an upper and a lower eye for attaching the hook to the fabric and with intermediate shank, the wire at the upper eye terminating in a laterally directed projection to afford with the intermediate shank a neck portion thereat about which the hook may be sewed to the fabric, and the wire at the lower eye terminating in a ring prong. 80

7. A one-piece heading hook for suspending fabrics, comprising a wire formed with an upper and a lower eye for attaching the hook to the fabric and with intermediate shank, the wire at the upper eye terminating in a laterally directed projection to afford with the intermediate shank a neck portion thereat about which the hook may be sewed to the fabric, and the wire at the lower eye being positioned adjacent said shank to form 90 a neck portion for further attachment of the hook to the fabric and then continued to form a ring prong whose free end is in juxtaposition to the lower eye for engagement therewith. 100

In testimony whereof I affix my signature.
DICKRAN M. SARKISIAN.
